UNITED STATES PATENT OFFICE.

LEROY C. DOANE, OF MERIDEN, CONNECTICUT, ASSIGNOR TO THE MILLER COMPANY, OF MERIDEN, CONNECTICUT, A CORPORATION OF CONNECTICUT.

DESIGN FOR A GLASS LIGHTING BOWL FOR BUS CEILINGS AND THE LIKE.

Application filed March 30, 1925. Serial No. 12,957. Term of patent 14 years.

To all whom it may concern:

Be it known that I, LEROY C. DOANE, a citizen of the United States, residing at Meriden, in the county of New Haven and State of Connecticut, have invented a new, original, and ornamental Design for Glass Lighting Bowl for Bus Ceilings and the like, of which the following is a specification, reference being had to the accompanying drawings, forming a part thereof.

Figure 1 is a bottom plan view of the glass lighting bowl made according to my design.

Figure 2 is a side elevation of the glass lighting bowl made according to my design.

I claim:

The ornamental design for a glass lighting bowl for bus ceilings and the like.

LEROY C. DOANE.
